UNITED STATES PATENT OFFICE.

WILLIAM HARRISON, OF LONDON, ONTARIO, CANADA.

GRAIN-BINDER.

SPECIFICATION forming part of Letters Patent No. 235,607, dated December 14, 1880.

Application filed September 25, 1879.

To all whom it may concern:

Be it known that I, WILLIAM HARRISON, of the city of London, in the county of Middlesex, Province of Ontario, Canada, have invented certain new and useful Improvements in Self-Binding Attachments for Reaping-Machines; and I do hereby declare the following to be a full, clear, and exact description of the same, reference being made to the accompanying drawings, forming a part of this specification, and in which

Figure 1 represents an end view of my improved attachment; Fig. 2, a view of rear end of carriage; Fig. 3, a side view of the mandrel and its bearings; Fig. 4, a bottom-plan view of tying apparatus; Fig. 5, an end view of table and clutch mechanism; Fig. 6, a detail view of the band-carrying arm, shifter, track, &c.; Fig. 7, a top-plan view of tying apparatus with table removed; Fig. 8, transverse sectional view through mandrel; Fig. 9, front end view of mandrel and hook; Fig. 10, detail view of parts composing mandrel and hook. Fig. 11, longitudinal vertical section of my improved attachment; Fig. 12, front elevation; Figs. 13, 14, and 15, detail views.

My invention relates to certain new and useful improvements in the class of self-binding attachments for reaping-machines using twine or cord for bands; and the invention consists in the novel construction, combination, and arrangement of parts, all as will be hereinafter fully described, and specifically pointed out in the claims.

To enable others skilled in the art to which my invention is most nearly connected to make and use the same, I will now proceed to describe its construction and operation.

In the drawings, A represents a table to be bolted to the rear end or any other convenient point of a reaping-machine.

B represents a chain-wheel loosely mounted on a shaft, b, passing through front end of table A, and connected to and operated from a chain-wheel on reaping-machine by an endless chain or other equivalent device.

The self-binding attachment is put into gear with the reaping-machine through the medium of clutch mechanism composed of a pivoted shifter, D, having a foot, d, adapted to engage with a stud, E, on the endless chain F, and a

spanner, G, engaging with a groove, H, in the clutch that engages with the wheel B, said shifter D being provided with a projecting arm, C, having a cord, a, connected thereto for operating the shifter.

By pulling on the cord a the shifter D is pulled around so that its foot falls off from the stud E on endless chain F, while at the same time the spanner G is actuated so as to force the clutch down until it engages with the wheel B, thus putting it into gear with the shaft upon which it is mounted, and thereby communicating motion to the chain-wheel K, rigidly secured upon the lower end of said shaft, through the medium of which motion is communicated to the endless chain F passing around said wheel K and a similar wheel, K'', mounted on a shaft near the center of the table.

L represents a rod having one end connected to the endless chain F and its other end pivoted to a bar, M, of the carriage, upon which is mounted the tying mechanism, and through the medium of which said carriage with the tying mechanism is reciprocated under the table A.

The carriage is connected to the under side of table by a bar, m, above the table, to which it is secured, said bar m working in a groove in the table as the carriage is reciprocated under it.

I represents a band-carrying arm, provided with a bobbin, J, containing the twine, said arm being pivoted to an arm, O, rigidly connected to and moving with the carriage. The arm I is provided with a foot, P, which moves over a spring-track, R, mounted upon and at one edge of the table, said track being provided with front and rear inclined grooves, S and Q, through which the foot of the arm I passes in its forward and backward movement, and engaging with a stud or foot, U, projecting from the table at the lower end of the slot Q, for a purpose to be hereinafter described.

W represents a spirally-grooved mandrel journaled in bearings on the under side of the carriage, and operated through the medium of the forked piece Z engaging with the spiral groove thereof. This mandrel is composed of the two parts w w', the part w being provided

with a curved projecting jaw, w^2 , and the part w' with a similar jaw, w^3 , forming a hook, V, at the front end of the mandrel when said parts are connected together. The portion w' is also provided with a collar, B', surrounding the portion w , and said collar is provided with a slot, C', through which passes a lug, d', on end of the stationary bar D'.

The sliding bar M of the carriage is provided with a stud, E', which engages with a shoulder on lever F' for the purpose of pressing the mandrel forward to open the jaws of the hook V, so that the band can pass between them.

15 G' represents a coiled spring surrounding the mandrel between the projecting pin v and the collar B' of the portion w' . This spring is for the purpose of forcing the portion w' of the mandrel with its hook w^3 forward, for a purpose hereinafter referred to.

J' represents a hook with its shank working in a groove in the side of the forward journal-box of the mandrel, for the purpose of retaining the free end of the band while it is carried 25 against and around the sheaf, and also for the purpose of gripping the band between it and the bar D' and cutting the band off by a shear cut against the knife O'. This hook is operated through the medium of the sliding 30 bar M, a stud, H', on the shank of the hook, engaging with a notch, I', on the sliding bar as it moves forward, thus carrying the hook forward and releasing the band until a stud, K', on the inner side of the shank of the hook 35 strikes an inclined shoulder, L', on the journal-box of the mandrel, which raises the hook so that the stud H' is thrown out of engagement with the sliding bar, when the hook is returned to its original position through the 40 medium of the spring M' and connecting-rod N', which movement of said hook gripes the band between it and the plate D' and shears it off against the knife O'.

Y represents a notch on the table, with which 45 a catch, X, on the carriage engages for the purpose of locking the carriage when it is at the position shown in Fig. 14, and also releasing the sliding bar M, which, in its further movement backward and return movement 50 forward, operates the mandrel and the other parts of the tying mechanism, as will be more fully referred to in the description of the operation of the machine.

P' represents a groove extending nearly 55 around the front portion of the mandrel, and in which a stud, n, on the carriage projects, so that in the revolution of the mandrel said stud forces the mandrel downward when it comes in contact with the portion, w' , not grooved, all 60 as clearly shown in Fig. 8, which movement is for the purpose of drawing the knot of the band tight.

The operation of my improved attachment is as follows: The carriage occupying the position shown in Fig. 12, with the foot P of the band-carrying arm resting in the inclined groove Q of the track R, and the free end of

the band held by the retaining-hook J' against the bar D', and a sheaf thrown across the front portion of the table A by the raking-off 70 arm of the reaper, the binding attachment is

thrown into gear with the reaper, as before described, so that the carriage is caused to move forward in the direction indicated by the arrow in Fig. 4, and the foot P, traveling up 75

the inclined groove Q, raises the arm above the table, in which position it is held. While the carriage is moving forward the sheaf is collected against the binding cord or band N, the foot of the band-carrying arm traveling 80

over the top of the track until it reaches the forward inclined groove, S, into which it falls. The motion being now reversed, said foot travels down the inclined groove S, which forces 85

the front end, T, of the band-carrying arm down through the opening t in the table A, carrying the band around the sheaf, said foot 90

traveling along the outer side of track as the carriage moves backward until it comes in contact with the foot U, when the track springs 95

out ready for the next forward motion of the carriage, with the foot P resting in the lower end of the inclined groove Q. When the front end of the band-carrying arm passes down 100

through the table, carrying with it the binding cord or band, it descends through the notch-formed lug of the hook V, projecting 105

from the front end of mandrel. The carriage having then moved to the rear end of the table, the catch X on the carriage falls into the 110

notch Y in the table, thus locking the carriage and releasing the sliding bar M, which is moved farther backward through the medium 115

of the chain F and rod L, and as said bar travels backward the forked piece Z, engaging 120

with the spiral groove in mandrel, causes it to be moved backward until the slot C' in the collar B' passes the lug d' on end of bar D', which movement of the mandrel causes the 125

hook V to catch and draw the band the thickness of said hook inside of the hollow mandrel before it starts to revolve, which backward movement of the hook forms half of the tying-loop. The mandrel and hook are now caused to 130

make about three-fourths of a revolution, both parts of the band passing outside of the hook when they commence to cross each other. At 135

this stage of the operation the stud E' on sliding bar M comes in contact with shoulder on lever F', pressing twisted mandrel forward and opening the jaws of the hook, which allows both ends of the band to pass between them. The slot C' in the collar B being now 130

opposite the stud d on bar D', the coiled spring G forces said collar with the upper jaw, w^3 , forward, thus gripping the two ends of the band between the jaws. The sliding bar M moving farther forward, the stud H' drops into notch I' on sliding bar, which carries the 145

curved retaining-hook J' forward, releasing the end of the band until the inner stud, K', of the shank of the hook J' strikes an inclined shoulder, L', throwing the stud H' out of engagement with the sliding bar, which permits 150

the hook J' , through the medium of spring M' and rod N' , to be quickly drawn back, gripping the band between it and the bar D' and shearing it off against the knife O' , leaving the free end of the band from the bobbin held by the retaining-hook against the bar D' to be carried around the next gavel in the manner above described.

The forward motion of the sliding bar above referred to also reverses the motion of the mandrel and hook V , so that the two ends of the band held by the jaws of the hook are drawn through the loop formed around the hook, which slips off of the tapering hook in completing the reverse movement, the stud n on the under side of carriage working in the eccentric groove P' , and at the point n' forces the hook and all its parts downward, which movement draws the knot tight. The forked piece Z , then pressing against the shoulder R' on twisted mandrel, opens the jaws of the hook, permitting the band to fall out, thus completing the tying operation. The stud E on chain F then comes under the foot of the shifter D , lifting the clutch H , and thus throwing the chain-wheel B out of gear, when the apparatus stands still until the next gavel is collected and thrown onto the table, when said wheel B is again thrown into gear through the medium of the shifter D and operating-lever and cord $C e$, and the above operation repeated.

It will be observed that I employ but one revolving mandrel carried in a hollow bearing, and by its own revolution it winds the cord around both ends of the tying-hook, and when about three-fourths of a revolution is made the jaws of the hook open and clamp between them the ends of the band. The ends are then cut off, when the mandrel is revolved in the reverse direction, allowing the loop of cord to slip off of the hook, retaining the two ends in its gripe, and the eccentric groove in the collar of the mandrel standing against the stud on the under side of carriage forces the end of the mandrel away from the carriage, thus drawing the knot tight.

I am aware that a hollow hooked cylinder or mandrel having a stationary inside mandrel in which works a smaller mandrel provided with a hook is old, and such I do not wish to be understood as claiming as my invention, it differing from my invention both in construction and operation.

Having thus fully described my invention, what I claim as new, and desire to secure by Letters Patent, is—

1. In a self-binding attachment for reaping-machines, the combination, with the shaft b , chain-wheel B , loosely mounted thereon, and grooved clutch H , of the pivoted shifter D , provided with a spanner, G , and foot d , and the endless chain F , provided with a stud, E , with which the foot of the shifter engages,

substantially as and for the purpose herein shown and described.

2. In a self-binding attachment for reaping-machines, the combination, with a table, A , provided with foot U , and spring-track R , having inclined grooves $Q S$, of a movable carriage, and a pivoted band-carrying arm, I , provided with foot P , and connected to and moving with said carriage, substantially as and for the purpose herein shown and described.

3. The combination of the twisted mandrel W , composed of the portion w , having the jaw w^2 , and the portion w' , having the jaw w^3 and slotted collar B' , the bar D' , provided with the stud d' , and the sliding bar M , having the forked piece Z , substantially as and for the purpose herein shown and described.

4. In a self-binding attachment for reaping-machines, the combination, with a vibrating band-carrying arm, of a twisted mandrel composed of the portions $w w'$, having curved projecting jaws $w^2 w^3$, forming the tying-hook V , and mechanism, substantially as described, whereby said mandrel is reciprocated and revolved and said jaws opened and closed for gripping and releasing the tying-band, substantially in the manner herein shown and described.

5. In a self-binding attachment for reaping-machines, the combination, with the tying mechanism, of the knife O' , bar D' , spring retaining-hook J' , sliding bar M , and connecting mechanism, whereby said hook is moved forward for releasing the band and returned to its original position for shearing off the band against the knife O' and retaining the free end of the band from the band-carrying arm, substantially as herein shown and described.

6. In a self-binding attachment for reaping-machines, the combination of the revolving mandrel, constructed substantially as described, and provided with the eccentric groove P' , and the carriage provided with a stud, n , working in said groove, whereby the mandrel and hook V are forced downward or away from the carriage for drawing the knot tight, substantially as herein shown and described.

7. In a self-binding attachment for reaping-machines, the revolving tying-hook V , composed of the movable jaws w^2 and w^3 , the shanks of said jaws moving in a longitudinal direction and independent of each other, whereby the two ends of the band are caught and the loop coiled around said jaws by their rotating movement and the ends drawn through the loop for tying the knot by the simultaneous longitudinal movement of the jaws, substantially as specified.

WILLIAM HARRISON.
